UNITED STATES PATENT OFFICE.

JOHN E. SWEET, OF SYRACUSE, NEW YORK, AND MILAN C. BULLOCK, OF CHICAGO, ILLINOIS.

DESIGN FOR AN UPRIGHT STEAM-ENGINE.

SPECIFICATION forming part of Design No. 13,842, dated April 3, 1883.

Application filed September 14, 1882. Term of patent 14 years.

To all whom it may concern:

Be it known that we, JOHN E. SWEET and MILAN C. BULLOCK, citizens of the United States, residing respectively at Syracuse, in the county of Onondaga and State of New York, and at Chicago, in the county of Cook and State of Illinois, have invented and produced a new and original Design for Upright Steam-Engines, of which the following is a specification, reference being had to the accompanying drawings, forming part thereof.

Our new design consists of a sort of columnar frame composed of a rectangular base and two straight converging uprights, which are united at the top by and terminate in the steam-cylinder and steam-chest, the uprights being broad at the base and tapering toward the top.

It further consists of such a columnar frame constructed with a cylindrical guide between the uprights and below the steam-cylinder.

In the annexed drawings, Figure 1 is a perspective view of an upright steam-engine constructed according to our new design. Fig. 2 is also a perspective view thereof, but taken from the opposite side.

A refers to the rectangular base, which is somewhat greater in length than in width, taking the length to be in the direction of the axis of the crank-shaft of the engine. The lower portions of the uprights B B, as high up as the crank-shaft, are formed on this rectangular base, across its width, one at each end, and they are united for a little distance up from the base by horizontal webs *aa*, which bound two sides of a well in the base, while the uprights proper bound the other two sides

of such well. The uprights are nearly as broad as the base at the junction therewith, but taper rapidly up to the crank-shaft, from which point they have a lesser taper up to the top. The uprights are straight shafts, which converge from the base A toward the steam-cylinder C and its chest D, by which they are united, and in which they terminate at the top. E refers to the cylindrical guide between the uprights below the steam-cylinder.

Having thus described our invention, what we claim, is—

1. The design for an upright steam-engine frame herein shown and described, which consists of a rectangular base and two straight converging uprights, broad at the base and tapering toward the top, where they are united by the steam-cylinder and steam-chest. 55

2. The design for an upright steam-engine frame herein shown and described, which consists of a rectangular base and two straight converging uprights, broad at the base and tapering toward the top, where they are united by the steam-cylinder and steam-chest, and the cylindrical guide between the uprights below the steam-cylinder. 60

In testimony whereof we affix our signatures in presence of two witnesses:

JOHN E. SWEET.
MILAN C. BULLOCK.

Sweet's witnesses:

HOWARD D. BURT,
ALBERT W. SMITH.

Bullock's witnesses:
